UNITED STATES PATENT OFFICE.

KARL TESSKY, OF ESSLINGEN, GERMANY.

MACHINE FOR GENERATING AND MARKING CAMS.

Application filed June 9, 1925, Serial No. 35,898, and in Germany June 7, 1924.

My invention relates to a machine for generating and marking cams which is equally suitable for generating or marking cams of the disc as well as of the end type, such cams being used for instance in connection with 5 automatic or semi-automatic machine-tools.

As a rule cams of the kind described are generated by means of a master cam, which involves the drawback that a separate master 10 cam is required for each type of cam to be generated.

It is an object of my invention to altogether eliminate the necessity of employing master cams and to provide simple, reliable and efficient means by which an infinite variation of 15 types of cams can be generated on a single machine by suitable adjustment.

To this end I provide a tool support which in generating the cam performs exactly the 20 same motion with regard to this cam which the roller of the cam lever will perform when the cam is in operation. As a rule such roller is mounted at the end of a cam lever and I therefore provide a rocking tool support of 25 exactly the same length as said cam lever and I arrange the fulcrum about which said support rocks in exactly the same position with regard to the axis of the cam, as the fulcrum of the cam lever when the cam is in operation.

30 A carriage is arranged to be reciprocated in the frame of the machine by means of suitable gearing, a guide arranged on this carriage being adapted to be adjusted at an angle to its direction of reciprocation. The guide is 35 operatively connected with the tool support in such manner that its reciprocation with the carriage is changed so as to impart motion to the tool support. The ratio at which such motion is transmitted is determined by the 40 angular position of the guide on said carriage.

By adjusting the guide on the carriage and by varying its rate of reciprocation it is possible to vary practically infinitely the motion of the tool support so that any desired number 45 of different cams can be generated on a single machine without requiring a master cam.

In the drawings affixed to this specification and forming part thereof a machine embodying my invention is illustrated diagrammatically 50 by way of example.

In the drawings:

Fig. 1 is an elevation,

Fig. 2 is a plan view of the machine, parts of the tool actuating mechanism being broken 55 away,

Fig. 3 is an end elevation of the tool carrying head,

Fig. 4 is a similar elevation showing a frame for supporting the arbour,

Fig. 5 is an elevation of a cam adapted to 60 be generated on the machine,

Fig. 6 is a plan view of the left hand end of 65 the machine, showing the gear box in which the arbour is supported, turned through an angle of 90 degrees, and

Fig. 7 is a detail.

Referring first to Fig. 5 of the drawings, 1 is a blank on which the curve 2 shall be generated so as to impart a predetermined motion 70 to a rocking lever diagrammatically indicated by the line 3, 4, which is fulcrumed at 4 and provided at 3 with the usual roller which is designed to run in contact with the cam. 6 is the axis of the cam, and *a* and *b* are the horizontal and vertical distances, respectively, 75 separating the fulcrum 4 from said axis 6.

Referring now to Figs. 3 and 4, the cutting tool 5, as a rule a milling cutter, is rotatably carried at one end of a support 9 which is seated on and adapted to rock about the driving shaft 13 of the tool-carrying head A. The length of the support 9, that is the distance between the axes of the tool 5 and the shaft 13 is equal to the length of the rocking 80 lever 3, 4 with which the finished cam is to cooperate and the axis 6 of the arbour 60 on which the blank for the cam 1 is chucked, is so located as to be at the correct horizontal and vertical distance *a*, *b* from the axis of the shaft 13, as shown in Fig. 4. 85

It will be understood that the length 3, 4 and the distances *a* and *b* are variable, and it is therefore necessary to make the support 9 exchangeable and to vary the relative position of the arbour 60 and the shaft 13 for each 90 type of cam to be marked or generated. In order to facilitate the location of the arbour 60 I provide an exchangeable frame 10 having an eye for the driving shaft 13 at one end and a bearing for the arbour 60 at the other end. 100 A third eye on the frame is adapted to receive a locating pin 11 for holding the frame 10 in position on the gear box 28.

Any suitable means which are well known in this art and therefore not shown and described, may be provided for adjusting the head A vertically and the frame C horizontally on a V-guide E and at right angles thereto.

Any suitable means may be provided for 110

imparting rotation to the cutter 5 from the driving shaft 18, for instance by gearing 51, 52 and 53, the intermediate gear 52 being mounted on the support 9 by means of a quadrant 54. Such gearing is well known in the art and need not be described in detail.

As mentioned, the support 9 is exchangeable in each individual case, and it will be understood that the support also absorbs

10 the reaction of the milling cutter or the component of such reaction which extends in the longitudinal axis of the support and the component is thus unable to effect an undesirable displacement of any part of the cutter 5.

The milling cutter 5 is conducted along the curve to be milled in the blank 1 by means of a push rod 12 linked to the support 9 at one end and to a rack 15 at the other. This rack

20 is slidably supported in a bracket B secured to the frame C of the machine, and its teeth 16 mesh with a segment 17 on a transverse shaft 18 which is also supported in the bracket B (Fig. 7). Another segment 19 is keyed

25 to the shaft 18 and meshes with a second rack 20 extending in parallel to the rack 15. A block 21 is adjustably secured in a slot of the rack 20 and adapted to engage a groove 22 in a straight edge 23. The straight edge is

30 adapted to be adjusted in an inclined position on a carriage 24, which can be displaced longitudinally by means of a screw spindle 25 in the frame C.

Rotation is imparted to the spindle 25 from 35 a pulley 26 through the medium of a gearing which is indicated in a general manner at D but is not described, as those skilled in the art are acquainted with mechanism of this kind. The gearing D also rotates a shaft 27,

40 which is rotatably carried in a gear box 28, and operates the shaft 29 of a worm 30 through the medium of bevel gearing 31. Worm 30 meshes with a worm wheel 32 keyed

45 on the arbour 60 so that the blank 1 is also rotated from the driving pulley 26. A reversing gear of some suitable type (not shown) is inserted between the shaft 25 and the gearing D, so that carriage 24 is automatically returned to its initial position after

50 having attained its opposite final position.

The reciprocation of the carriage 24 imparts a corresponding reciprocation to the rod 12 and to the support 9 of the milling cutter 5. The curve generated in the blank

55 1 will correspond to the position of the straight-edge 23 and the ratio at which the slide 24 is reciprocated and the blank 1 is rotated from the gearing D. Curves of any shape and gradient may be generated on the entire perimeter of the blank or on a part thereof, as desired.

As illustrated in Fig. 6, the gear box 28 is adapted to be displaced from its position in Fig. 2 through an angle of 90 degrees. A shaft 33 is rotatably supported in the gear

box 28 and connected with the shaft 27 through the medium of the bevel gearing 31. In the position shown in Fig. 6 the last wheel of the gearing D is keyed to the shaft 33, instead of the shaft 27, and this shaft is now 70 running idle while the shaft 33 imparts rotation to the arbour 60. In this case the workpiece is a blank 100 and the curve is generated at its end by the cutter 5.

If it is desired to mark a cam instead of 75 generating a curve thereon, the milling cutter 5 is exchanged for a marking implement (not shown).

I wish it to be understood that I do not desire to be limited to the exact details of 80 construction shown and described, for obvious modifications will occur to a person skilled in the art.

I claim:—

1. A machine for generating the faces of 85 cams which cooperate with rollers on rocking levers, comprising a frame, a chuck on said frame for holding a blank, a tool support in the shape of a rocking lever of a length equal to that of the cam lever in a machine of which said cam-and-lever-unit 90 will form part, said rocking lever being pivoted on said frame in a position with respect to said blank which corresponds to the relative position of the finished cam and the pivot of its cooperating rocking lever, a tool carried on said support in a position corresponding to the roller of said cooperating rocking lever, a carriage adapted to reciprocate on said frame, a slide bar supported on said carriage, and means for connecting said slide bar with said tool-supporting rocking lever so as to transmit the reciprocation of said carriage to said rocking lever at a ratio 95 corresponding to the adjustment of said slide bar with respect to said carriage.

2. A machine for generating the faces of 100 cams which cooperate with rollers on rocking levers, comprising a frame, a chuck on said frame for holding a blank, a tool support in the shape of a rigid exchangeable rocking lever of a length equal to that of the cam lever in a machine of which said cam-and-lever-unit 105 will form part, said rocking lever being pivoted on said frame in a position with respect to said blank which corresponds to the relative position of the finished cam and the pivot of its cooperating rocking lever, a tool carried on said support in a position corresponding to the roller of said cooperating

110 rocking lever, a carriage adapted to reciprocate on said frame, a slide bar supported on said carriage, and means for connecting said slide bar with said tool-supporting rocking lever so as to transmit the reciprocation of said carriage to said rocking lever at a ratio 115 corresponding to the adjustment of said slide bar with respect to said carriage.

3. A machine for generating the faces of 120 cams which cooperate with rollers on rocking levers, comprising a frame, a chuck on said frame for holding a blank, a tool support in the shape of a rigid exchangeable rocking lever of a length equal to that of the cam lever in a machine of which said cam-and-lever-unit 125 will form part, said rocking lever being pivoted on said frame in a position with respect to said blank which corresponds to the relative position of the finished cam and the pivot of its cooperating rocking lever, a tool carried on said support in a position corresponding to the roller of said cooperating

130 rocking lever, a carriage adapted to reciprocate on said frame, a slide bar supported on said carriage, and means for connecting said slide bar with said tool-supporting rocking lever so as to transmit the reciprocation of said carriage to said rocking lever at a ratio 135 corresponding to the adjustment of said slide bar with respect to said carriage.

In testimony whereof I affix my signature.
KARL TESSKY.
